UNITED STATES PATENT OFFICE.

LEIGH R. EVANS, OF ROCHESTER, NEW YORK, ASSIGNOR TO CYCLEMOTOR CORPORATION,
OF ROCHESTER, NEW YORK, A CORPORATION OF NEW YORK.

CARBURETER.

1,263,047.

Specification of Letters Patent. Patented Apr. 16, 1918.

Application filed December 18, 1915. Serial No. 67,690.

To all whom it may concern:

Be it known that I, LEIGH R. EVANS, a citizen of the United States, and a resident of the city of Rochester, in the county of Monroe and State of New York, have invented a new and useful Carbureter, of which the following is a specification.

This invention relates to carbureters for gasolene engines, and more particularly to carbureters for engines using the two-stroke cycle.

One of the objects of this invention is to devise a simple and efficient carbureter for gasolene engines which can be cheaply made and assembled and which can be attached directly to the engine cylinder.

A further object of the invention is a carbureter for gasolene engines using the two-stroke cycle which does not require any check valve.

A further object is to simplify and improve the construction of carbureters in general, particularly by reducing the number of parts and the number of operations required to make these parts and assemble them.

Further objects and advantages will appear as the description progresses.

The invention consists in the parts, and in the combinations and arrangements of parts, which are more fully described hereinafter and particularly pointed out in the appended claims.

In the accompanying drawing in which is illustrated the preferred physical embodiment of the invention and in which like reference characters refer to like parts in the several views, Figure 1 is a top plan view of a carbureter embodying the invention, showing the same attached to a portion of an engine cylinder; Fig. 2 is a vertical section through the float chamber, showing the rest of the carbureter in elevation, said section being taken substantially on the line 2-2 in Fig. 1; Fig. 3 is a transverse vertical section diagonally through the float chamber and crosswise of the mixing tube, said section being taken substantially on the line 3-3 in Fig. 1; Fig. 4 is a vertical longitudinal section through the mixing tube and nozzle, said section being taken substantially on the line 4-4 in Fig. 1; Fig. 5 is a horizontal section taken substantially on the line 5-5 in Fig. 3; Fig. 6 is an end view of the carbureter looking from the right in Fig. 1, the cover cap for the intake opening of the mixing tube being removed; and Fig. 7 is a top plan view of the nozzle forming part of the carbureter.

Referring in detail to the accompanying drawing, the carbureter comprises a main casting or body portion A, which is shown attached to a portion of the engine cylinder, designated B, by screws 5; a gasket 6 being interposed between the carbureter and said engine cylinder to make a gas tight joint. The carbureter is intended to be placed over the inlet port of the engine and is provided with a rectangular opening 7, shown in Fig. 2, designed to register with said inlet port; and this opening 7 communicates with a mixing tube or conduit 8 which extends longitudinally of the body portion A of the carbureter. This mixing tube 8 is preferably so proportioned that its cross sectional area is smallest throughout a region between its ends, particularly at the point where the nozzle, hereinafter described, extends into the mixing tube 8, this proportioning of the cross sectional area being in accordance with the well known principle of the Venturi tube. The outer end of the mixing tube 8 has flaring walls forming a bell-shaped end, around which is an annular flange 9, see Fig. 6; and located within the edge of this bell-shaped end of the mixing tube 8 are two oppositely disposed lugs 10. A circular baffle plate 11, which is a little smaller in diameter than the diameter of the inside of the bell-shaped end of the mixing tube 8, fits against these lugs 10; and a cap 12 having an annular flange 13 adapted to fit around the annular flange 9 is fastened over the end of the mixing tube 8 over the baffle plate 11 by two screws 14, said cap 12 having a central circular hole 15 therein.

Cast integral with the body portion A of the carbureter are the walls and bottom of a cylindrical float chamber 16; and in this float chamber 16 is the usual float 17 secured to a valve rod 18, the lower end of which is guided in a cylindrical recess in the bot-

2
 tom of the float chamber 16, and the upper end of which is pointed. The pointed upper end of the valve rod 18 co-operates with a conical valve seat 19 in a plug 20 secured in an elbow member 21 integral with the top 22 of the float chamber 16. This elbow member 21 is provided with a suitable union 23 for attaching the gasoline supply pipe (not shown) thereto, the gasoline being conducted to the valve seat 20 along passages 25 and 26. In the cover 22 is a vent hole 24, as shown in Fig. 1. The cover 22 is provided with an annular flange 27 which fits inside of the float chamber 16, and is fastened to said float chamber by a screw 28 and by a thumb nut 29 on the threaded needle valve 30, a washer 31 of leather or other suitable material being placed under the thumb nut 29 to prevent the escape of gasoline which may pass by capillary action up along the screw threads on the needle valve 30. The lower end of the needle valve 30 is tapered and projects into a conical hole 32 in the bottom of a recess 33 which opens into the float chamber.

Integral with the body portion A of the carbureter and projecting downwardly below the mixing tube 8 is a rib 34 in which is a vertical threaded hole 35 communicating with the tapered hole 32 in which the needle valve 30 projects by a horizontal passage 36 closed at its outer end by a screw 37, which facilitates manufacture and permits cleaning. In the threaded hole 35 is screwed a nozzle 38 having a hexagonal head 39 by means of which it is screwed in place and an axial bore 40 closed at its lower end by a screw 41. Surrounding the nozzle 38 near its lower end is a groove 42 which communicates with the axial bore 40 in said nozzle by a transverse bore 43, the groove 42 being located in the same plane as the passage 36. The upper end of the nozzle 38 is tapered, and in this tapered end portion is a small vertical jet passage 44 leading down into the axial bore 40 and a number of inclined jet passages 45 arranged around the central jet passage 44 in a circle and also leading down into the axial bore 40.

50 The operation of the carbureter is as follows: The gasoline flows from a suitable supply tank or reservoir (not shown) through the usual supply pipe and through the passages 25 and 26 into the float chamber 16; and when the gasoline has risen to a certain level in this float chamber, the float 17 seats the pointed end of the valve rod 18 against the seat 19 in the plug 20 and shuts off further supply of gasoline. On the suction stroke of the engine air is drawn through the central opening 15 in the cap 12, around the annular space between the baffle plate 11 and the inside edge of the flared end of the mixing tube 8 and along said mixing tube over and around the nozzle 38. The rapidly moving current of air over the nozzle 38 sucks gasoline through the jet passages 44 and 45 into the mixing tube 8 in a finely divided spray, and this gasoline is mixed with the air to form the desired explosive mixture. Since the area of the cross section of the mixing tube 8 at the point where the nozzle 38 projects into said mixing tube is smaller than the cross sectional area at the inlet opening 15 and the opening 75 7 communicating with the engine cylinder, the velocity of the air as it passes the nozzle 38 is higher than at either the entrance or the discharge end of said mixing tube; and in this way, for the same difference in pressure between the inside of the engine cylinder and the outside air, a greater suction is exerted on the jet passages 44 and 45 than would be exerted if the mixing tube were of uniform cross sectional area. This causes a more ready response of the gasoline to relatively small suction pressures at low piston speeds, and also causes the gasoline to be sprayed into the mixing tube at the very beginning of the suction stroke. It is also noted that the jet passages 44 and 45 extend in a direction transversely of the mixing tube 8, so that the spray from these jet passages impinges against the upper curved face of the mixing tube 8 and is further atomized. The rate of the flow of the gasoline to the nozzle 38 can be regulated by loosening the thumb nut 29 and adjusting the needle valve 30, thereby permitting the proportion of gasoline and air to be nicely regulated, as required.

55 In the common type of gasoline engine using the two-stroke cycle, with which I am familiar, the inlet port is controlled by the piston of the engine; and there is a short interval of time in the compression stroke during which a certain portion of the carbureted air in the crank case is expelled. This expulsion of carbureted air takes place through the same passage by which the carbureted air is drawn into the crank case and in which is located the inlet supplying gasoline to the inflowing air. The means for supplying gasoline is often in the form of a jet through which the gasoline, and also lubricating oil in case lubricating oil is mixed with the gasoline, is drawn by the suction of the piston on the intake stroke.

60 On the intake stroke of the engine the flow of gasoline through the jet does not cease immediately after the piston finishes its intake stroke, because of the inertia of the moving liquid; and consequently, a larger quantity of mixed gasoline and lubricating oil is drawn from the jet than can be taken up by the inflowing air. Upon the compression stroke, as before stated, part of the carbureted air in the inlet passage to the engine is driven outward toward the carbureter, and this carbureted air in turn forces air which

is in the tube surrounding the jet outward through the carburetor, the result being that a large proportion of the excess of mixed gasoline and lubricating oil around the jet is picked up and carried along mechanically; and, if the carburetor passage were open, this mixed gasoline and oil would be thrown out of the carburetor.

The expulsion of lubricating oil and gasoline by the action above described causes a serious loss of fuel and oil, not to mention the disagreeable effects resulting from the contact of the oil and gasoline with anything which may happen to be close to the intake opening of the carburetor. With some types of engines and under some conditions, this expulsion of gasoline and oil might not cause serious damage; but when a carburetor is applied to a motor for propelling a bicycle or the like, it can not be easily placed where it will be convenient and accessible and at the same time in a position where oil and gasoline expelled from it will not spatter on the clothes of a person riding the bicycle.

According to this invention, however, the baffle plate 11 is positioned in the direct path of outward movement of the expelled gasoline and oil and prevents such gasoline and oil from being thrown out of the mixing tube 8. Also, this gasoline and oil, instead of being wasted, is held mechanically by the lower portion of the enlarged outer end of the mixing tube 8 and is in the direct path of inflowing air, so that it is taken up by such air on the next intake stroke of the piston and returned to the engine. It should also be noted that while the baffle plate 11 prevents the expulsion of oil and gasoline, it does not materially increase the opposition to the intake of air, because the inflowing air has to make only one sharp turn around the edge of the baffle plate.

The simplicity of the whole construction of the carburetor embodying the invention is apparent, and the ease and cheapness with which the different parts may be manufactured and assembled is also apparent. The cover 22 to the float chamber 16 may be easily and quickly removed to permit cleaning of the float chamber and of the valve seat 19. In the same way the needle valve 30 can be quickly removed for cleaning purposes, and by removing the screw 37 convenient access is had to the horizontal passage 36. The nozzle 38 may be unscrewed from place and the jet passages cleaned, or the screw 41 may be removed for cleaning the axial bore 40 in the nozzle. In this way the different passages and holes which are likely to be clogged by foreign particles in the gasoline can be easily and quickly cleaned without detaching the carburetor from the engine.

Obviously various changes may be made in the particular construction shown and

described without departing from my invention, and I do not wish to be restricted to the details of this construction illustrated which exemplifies only one form or embodiment which my invention may take.

What I claim is:

1. A carburetor for engines using the two-stroke cycle comprising a mixing tube, means for atomizing a liquid in said mixing tube, said mixing tube having its inlet end flared and having lugs integral therewith the outer faces of which are substantially flush with the outer inlet end of said mixing tube, a baffle plate slightly smaller than the inside periphery of the flared end of said mixing tube, a convex cap fitted over the flared end of said mixing tube and having a central opening therein smaller than said baffle plate, the edge of said cap forming a tight joint with the edge of the flared end of said mixing tube, and screws extending through said cap and baffle plate into said lugs.

2. A carburetor for engines using the two-stroke cycle comprising a mixing tube, means for atomizing a liquid in said tube, a baffle plate located adjacent the air intake end of said mixing tube, said baffle plate being smaller than the inside periphery of said tube, means carried by the wall of said mixing tube for supporting said baffle plate in proper position, and a cap having a central opening therein smaller in size than said baffle plate, said cap being secured tightly to the end of said tube outside of said baffle plate.

3. A carburetor comprising a mixing tube arranged substantially horizontally, means for atomizing a liquid in said mixing tube, a baffle plate secured over the air intake end of said mixing tube and smaller than said intake end, a cap secured over the inlet end of said mixing tube and having a central opening therein, said tube and cap being constricted in cross section on each side of said baffle plate, whereby a pocket for catching liquid is formed under said baffle plate.

4. In a carburetor for gasoline engines, in combination with a mixing tube, the air intake end of said mixing tube being flared outwardly, a baffle plate secured over the flared end of said mixing tube, said baffle plate being smaller than the inside periphery of said flared end of said mixing tube, a cap disposed over said baffle plate and spaced therefrom, said cap fitting tightly around its edge against the flared end of said mixing tube and having a central opening therein smaller than said baffle plate, means whereby said baffle plate is held in place between said cap and the end of said mixing tube, and means for atomizing a liquid in said mixing tube.

5. In a carburetor for gasoline engines, a mixing tube, a float chamber integral with

4
said mixing tube and having an open top, a cover for said float chamber having an inlet passage therein, means within said chamber controlled by the level of liquid 5 therein for governing the flow of liquid through said inlet passage, a nozzle projecting into said mixing tube and communica-

cating with said float chamber, a needle valve for regulating the flow of liquid from said float chamber to said nozzle, said needle 10 valve projecting through said cover, and a thumb nut on said needle valve for holding said cover in place.

LEIGH R. EVANS.
